Primary Examiner—Freda Nunn

[57] CLAIM

The ornamental design for the front face of a vehicle wheel,
as shown and described.

DESCRIPTION

FIG. 1 is a front elevational view of the front face of a vehicle wheel showing my new design; and,
FIG. 2 is a front perspective view thereof, it being understood that the broken line showing of the outer surface of the rim is for illustrative purposes only and forms no part of the claimed design.
